UNITED STATES PATENT OFFICE.

ELIJAH CULVER, OF GRAND RAPIDS, MICHIGAN, AND CHARLES A. HASCALL,
OF HURLEY, WISCONSIN.

SHIRT.

SPECIFICATION forming part of Letters Patent No. 485,490, dated November 1, 1892.

Application filed December 28, 1891. Serial No. 416,346. (No model.)

To all whom it may concern:

Be it known that we, ELIJAH CULVER, residing at Grand Rapids, in the county of Kent and State of Michigan, and CHARLES A. HASCALL,
5 residing at Hurley, in the county of Ashland and State of Wisconsin, citizens of the United States, have invented certain new and useful Improvements in Shirts, of which the following is so full, clear, and exact a description as
10 will enable others skilled in the art to which our invention appertains to make and use the same, reference being had to the accompanying drawings, in which—

Figure 1 of Sheet 1 is a perspective view of
15 a shirt embodying our invention, showing the shirt buttoned and closed. Fig. 2 of Sheet 2 is a perspective view of the same, showing the shirt unbuttoned and open.

In the accompanying drawings, A designates the main body of the shirt, to one side of the upper front portion of which is secured the bosom B, which has a free edge D and which is provided with fastening devices *a—a*—one at the upper free outer corner and one at
20 a central point in the neckband in the front. For convenience we show buttonholes to be used with ordinary collar-buttons, and we prefer such mode of fastening; but we do not limit this invention to such forms of fastenings, as any suitable device may be used. The bosom is free along one-half of its bottom and is separated from the shirt by a notch, and the skirt of the shirt has an overlapping fly E, which is adapted to be secured to the
25 opposite side of the opening by a button *b* at its upper free corner, while the opposite side of the flap is fastened to the fly E at *d* at a point about on the line of the center of the bosom, thus providing a double skirt in front
30 which is easily opened on account of its free overlapping edges.

The neckband proper F of the shirt A is connected with the bosom B in front only as far as the center. At G the bosom is "recessed,"
45 so to speak, and the bosom extends on a line below the bottom of the neckband up to the

point of fastening, and the neckband F extends around from the point G to the same point, where it laps and is fastened by any fastening, but preferably by a collar-button. 50 By this means there is no unusual thickening of the neck portion where the bosom overlaps the body of the shirt.

The advantage of having the bosom free at the bottom is twofold. First, it prevents the 55 bosom from doubling up, and, second, it is cooler and prevents the bosom from being pushed up from the bottom and forcing the collar-button and neckband against the neck
60 of the wearer.

By separating the skirt-flap E from the bosom it enables the wearer to open the flap without disturbing the bosom, and by having the skirt overlap as it does it makes the skirt double at that point, making a complete cover 65 for the wearer that will not accidentally open or gap, and at the same time, when desired, it may be readily opened and closed at will.

What we wish to secure by Letters Patent, and what we therefore claim, is—
70

A shirt open in front from top to bottom and having an overlapping bosom attached to one of the flaps and adapted to overlap the opposite flap and provided with means for securing the free edge of the bosom to the 75 side opposite the side to which it is permanently secured, the skirt of the shirt having an overlapping-flap portion E, which is separated from the lower outer portion of the bosom by a notch, said flap portion E adapted 80 to overlap and be secured to the opposite side of the skirt, substantially as described.

In testimony whereof we affix our signatures in the presence of two witnesses.

ELIJAH CULVER.

CHARLES A. HASCALL.
